No. 799,453.

PATENTED SEPT. 12, 1905.

G. G. COMER.
EXTENSION CAR STEP.
APPLICATION FILED MAY 11, 1905.

UNITED STATES PATENT OFFICE.

GEORGE GRANT COMER, OF KALAMA, WASHINGTON, ASSIGNOR OF ONE-THIRD TO AMOS ALBRO BURK AND ONE-THIRD TO ELZA N. HOWE, OF KALAMA, WASHINGTON.

EXTENSION CAR-STEP.

No. 799,453.

Specification of Letters Patent.

Patented Sept. 12, 1905.

Application filed May 11, 1905. Serial No. 259,891.

To all whom it may concern:

Be it known that I, GEORGE GRANT COMER, a citizen of the United States, and a resident of Kalama, in the county of Cowlitz and State of Washington, have invented a new and Improved Extension Car-Step, of which the following is a full, clear, and exact description.

This invention relates to improvements in extension-steps for passenger cars or coaches, the object being to provide extension-steps that may be readily attached to the ordinary fixed steps and so arranged as to be easily moved to and held in its lowered position and moved automatically to its upper position when not required for use.

I will describe an extension car-step embodying my invention and then point out the novel features in the appended claims.

Reference is to be had to the accompanying drawings, forming a part of this specification, in which similar characters of reference indicate corresponding parts in both the figures.

Figure 1 is a perspective view of a portion of a car, showing an extension-step embodying my invention; and Fig. 2 is a front view thereof, partly in section, on the line 2-2 of Fig. 1.

Referring to the drawings, 5 designates the ordinary car-step fixed to the side boards 6. The extension-step 7 has extended upward from its ends rods 8 9, the rod 8 being guided between two pairs of curved rollers 10 11, mounted on a metal plate (preferably steel) 12 to one of the side boards 6. The rod is also movable through a bracket 13, extended outward from the said plate 12, and a spring 14 surrounds the rod, engaging at its lower end with the bracket 13 and at its upper end with a cross-head 15, rigidly secured to the rod 8. The rod 9 is also guided between a pair of lower rollers 16 and a pair of upper rollers 17, and a bracket 18, secured to a metal plate 19 on the front side board of the steps, has a perforation in which the rod 9 is movable. A spring 20 surrounds the rod 9, engaging at its lower end with the bracket 18 and at its upper end with a cross-head 21, attached to the said rod 9. The step is limited in its downward movement by the cross-heads 15 and 21 engaging the upper sides of pins 22, extended outward from the plates 12 and 19.

The front rod 9 is moved outward underneath the platform-sill 23, the said sill having a recess 24 on its under side to permit said portion 25 to move sufficiently upward to bring the extension-step up against the under side of the lower step 5. From the outwardly-turned portion 25 the rod is continued upward in front of the sill, as indicated at 26, and above the sill it is provided with a foot-plate 27. If desired, the part 26 may be still further continued upward between guides 28 on the platform-rail 29 and provided at its upper end with a handpiece 30. It is to be understood, however, that the rod may be operated wholly by foot-pressure. On the upward extension 26 of the rod is a lug 31, designed to engage against the under side of the sill 23 to hold the extension-step in its lowermost position. A spring 32, attached to the sill 23 and engaging against the outer side of the rod-section 26, will serve to force the lug 31 underneath the sill.

In the operation when it is desired to lower the extension-step the section 26 of the rod is to be forced downward, and as it is somewhat resilient when the inclined lower edge of the lug 31 engages with the sill 23 the said rod-section 26 will move upward, permitting the lug to pass down the outer side of the sill until it is moved underneath.

Having thus described my invention, I claim as new and desire to secure by Letters Patent—

1. The combination with fixed steps of a car, of an extension-step, rods extended upward from the ends of said extension-step, guides on the side boards of the fixed steps between which said rods move, perforated brackets on said side boards through which the rods pass, cross-heads on the rods, springs arranged between said cross-heads and said brackets, one of said rods having an upward extension, and means for holding the extension-step in lowered position.

2. The combination with fixed steps of a car, of an extension-step, rods extended upward from the ends of said step, guides on the side boards of the fixed steps between which said rods move, perforated brackets on said side boards through which the rods pass, cross-heads on the rods, springs arranged between said cross-heads and said brackets, one of said rods having an upward extension, a lug on

said extension for locking the extension-step in lowered position, and a spring for moving the lug to locking position.

3. The combination with fixed steps of a car, 5 of metal plates secured to the outer sides of the step, side boards, upper and lower pairs of rollers on said plates, perforated brackets on said plates, an extension-step, rods extended upward from said step and engaging between the rollers, and also passing through 10 the perforations of the brackets, cross-heads on said rods, springs surrounding the rods and engaging at their lower ends with the brackets and at their upper ends with said cross-heads, 15 pins adapted to be engaged by the cross-heads

to limit the downward movement of the step one of said rods having an upward extension, a lug on said extension designed for engaging the under side of the car-platform sill, a foot-plate on said upward extension, and a spring 20 attached to the car-platform sill and engaged to the outer side by said upward extension.

In testimony whereof I have signed my name to this specification in the presence of two subscribing witnesses.

GEORGE GRANT COMER.
